THOMAS ARTHUR JOHNSON, OF ROCKFORD, ILLINOIS.

BOTTLE-STOPPER PROTECTOR AND SUPPORTER.

1,352,967.

Specification of Letters Patent. Patented Sept. 14, 1920.

Application filed February 14, 1920. Serial No. 358,659.

To all whom it may concern:

Be it known that I, THOMAS ARTHUR JOHNSON, a citizen of the United States, residing at Rockford, in the county of Winnebago 5 and State of Illinois, have invented a new and useful Bottle-Stopper Protector and Supporter, of which the following is a specification.

This invention relates to bottle stopper 10 protectors and supporters.

The object is to provide a simple device for use in conjunction with medicine or chemical bottles or similar receptacles to be engaged with the corks or stoppers thereof 15 for the purpose of facilitating the removal of the same from the necks of the bottles, and when so removed to support the same upon a table, shelf, etc., in such manner as to prevent the small end of the cork or stopper which usually carries some of the 20 contents of the bottle or receptacle thereon, from coming into contact with the supporting surfaces, and at the same time protecting the cork or stopper from contamination 25 by adhering foreign substance or matter which might result from such contact, the device being so constructed as to attain these desired results, no matter in what position the cork or stopper together with the 30 supporting device may be placed upon said support.

A full and complete understanding of the invention may be obtained from a consideration of the following detailed description, 35 taken in connection with the accompanying drawing forming part of this specification; it being understood that while the drawing shows practical forms of the invention, the latter is not confined to strict 40 conformity therewith but may be changed or modified, so long as such changes or modifications mark no material departure from the salient features of the invention, as specifically pointed out in the appended claims.

In the drawing, in which similar reference characters designate corresponding parts throughout the several figures:—

Figure 1 is a side elevation of the upper portion of a bottle having the improved device applied thereto and in engagement with the cork or stopper.

Fig. 2 is a plan view of the device attached to a cork.

Fig. 3 is a perspective view of the device 55 supporting a cork upon a table or similar surface.

Fig. 4 is a side elevation of a modified form of the device attached to a cork.

Fig. 5 is a similar view of another modified form, the cork or stopper being shown 60 in dotted lines.

Figs. 6 and 7 are detail views showing other methods of connecting the attachment to a cork or stopper without employing a cork screw.

The preferred embodiment of the invention, as illustrated in Figs. 1, 2 and 3 of the drawing, is formed of a length of suitable stiff, spring wire, such as is used in the manufacture of the cheaper grade of cork 70 screws, bent to form an extracting ring or handle 1 of a diameter to freely receive the finger of the operator, the said loop being formed nearer to one end of the strand of wire than the other, the said end portions 75 being twisted about each other two or more times, as at 2, in order to hold the loop 1 from springing open. The shorter end of the wire strand is then twisted into an ordinary cork screw 3, or other form of attach- 80 ing means, the longitudinal axis of which is arranged in radial relation to the center of the extracting loop 1 in the usual manner.

The other or longer end portion of the wire strand is bent at substantially right 85 angles to the axis of the cork screw 3 and the twisted portion 2 at the point where the latter parts join, as indicated at 4, and extends outwardly a distance sufficiently beyond the diameter of the mouth of the 90 maximum sized bottle as to avoid contacting with the same, and is thence bent downwardly to form a supporting arm 5 in a direction parallel with the axis of the cork screw, and a considerable distance beyond 95 the penetrating point of the same, where the wire is then bent at right angles to the arm 5 and curved inwardly and around a center in alignment with the axis of the cork screw and in spaced relation thereto 100 to form a guard ring or loop 6, whose diameter is such as to freely pass over the beaded mouth end of the maximum sized bottle, the terminal of the longer end of the wire strand composing the device being 105 wrapped about the lower portion of the arm 5, to firmly hold the loop 6 in position, as indicated at 7.

As illustrated in Fig. 1, the ring or loop 6 is passed over the beaded mouth end 8 110 of the bottle 9, the said ring being held by the arm 5 in spaced relation to the neck

of the bottle and from the bottle proper, the device being then rotated by the finger of the operator through the ring or loop 1, to drive the cork screw 3 into the usual 5 cork 10, which may be readily extracted from the bottle, or replaced in position, without any interference whatsoever by the guard ring or loop 6.

When the device together with the cork 10 is removed from the bottle, the same may be carelessly placed upon a table, shelf or other support, when the same will assume the position shown in Fig. 3 of the drawing, the longitudinally disposed arm 5 serving through its weight to rock the device together with the cork until the said arm rests upon the table when the device is held stationary, the ring 6 and the large end of the cork 10 serving at all times to prevent the small end of the same from contacting with the support thus preventing any of the contents of the bottle, which may be highly injurious and which may be adhering to the small end of the cork, from 20 affecting said surface, or from becoming contaminated with foreign substance or matter picked up from such surface.

In Fig. 4, the extracting loop or ring 1 is omitted, and consequently the twisted 30 portion 2, the rest of the device being formed substantially the same as that shown in the preceding figures, and this form of the device is especially adapted for use upon shelves where economy of space is demanded 35 and the room necessary for the rings or loops 1 is not present.

The form of the device illustrated in Fig. 5 is similar to those previously described in so far as it has the cork screw 3 and the 40 guard ring 6 connected together in the same manner, but the extracting ring 1 and the twisted portion 2 are omitted, as in the second described form, illustrated in Fig. 4, and in lieu thereof the horizontally disposed arm 4 is connected directly to the cork screw 3 being looped to form an eye 11, through which a swiveled extracting 45 ring 12 is engaged, said ring 12 being adapted to lie upon the top of the cork when not in use, and thus obviate the necessity for additional room at the top of the bottle to provide for the extracting ring.

The last two described forms of the invention are particularly well adapted to be applied to bottles of drugs, chemicals, etc., and to be carried by the same during shipment, being easily inclosed in cartons or wrapped in packages and occupying substantially no additional room.

From the foregoing it will be seen that 60 an extremely simple and efficient device for the purposes stated has been provided, which can be manufactured at a low cost and placed upon and sold with the bottle with slight additional cost thereof, the device

serving to protect the contents of the bottle from contamination by preventing the inserted end of the cork from contacting with any surface or support upon which it might be placed when extracted, and at the same 70 time prevents soiling or marking such support.

In Figs. 6 and 7 other modified forms of the invention are shown. In Fig. 6, the longitudinal arm carrying the guard loop is 75 shown as being molded or seated in an opening of a glass stopper.

In Fig. 7, the attachment is shown as being twisted or wrapped around the upper part of the cork. The latter may be a glass 80 stopper or an ordinary cork.

The essential feature of the invention consists in the guard loop 6 of greater diameter than the neck of the bottle and necessarily of greater diameter than the cork itself, said 85 guard loop being carried by a longitudinal arm whereby when the cork is detached, the loop holds the lower end of the cork out of contact with the supporting surface.

What is claimed is:—

1. An attachment for bottle stoppers serving as a protector and supporter for the stopper, comprising a longitudinal arm having at one end a means of attachment to the stopper and at the other end a guard loop of a size to slip over the neck of the bottle, said 95 loop holding the end of the stopper out of contact with a supporting surface when the stopper is removed from the bottle, and a loop or handle provided at the end opposite 100 the guard loop by means of which the attachment may be manipulated.

2. An attachment for bottle stoppers comprising a longitudinal arm having at one end a cork screw and at the other end a guard 105 loop of a size to pass over the neck of a bottle and serving as a support for the stopper when the latter is removed from the bottle.

3. A bottle stopper protector and supporter formed of a single strand of wire bent to form a corkscrew, an arm extending at right angles to the axis of the corkscrew from the end thereof remote from the penetrating end, said arm being bent at right 115 angles and in parallelism to the axis of the corkscrew and extending beyond the penetrating end thereof, and then being bent again at right angles, and curved into circular form to provide a guard ring or loop 120 whose center is in alignment with the longitudinal axis of the corkscrew.

4. A bottle stopper protector and supporter formed of a single strand of wire bent intermediate its length to form an extracting ring located nearer to one end of the wire than the other, said ends being twisted about each other, the shorter end being formed into a corkscrew whose longitudinal axis is in alignment with the diam- 130

ter of the ring, the longer end of the wire being bent outwardly at substantially right angles to the corkscrew and at the end thereof remote from the penetrating end, to form an arm extending beyond the mouth end of a bottle, said arm being then bent parallel to the corkscrew and extending beyond the end thereof a sufficient distance to clear the lower end of the cork and there formed into a loop concentric with the axis of the corkscrew and adapted to surround the neck of a bottle when the cork is applied thereto and to support the smaller end of the latter in spaced relation to a supporting surface when re-
moved therefrom.

5. An attachment for bottle stoppers serving as a protector and supporter for the stopper, comprising a longitudinal arm having at one end means for rigidly attaching

the same to the stopper, and at the other end 20 a guard loop having a greater diameter than the neck of the bottle as well as the stopper so as to permit the stopper to be applied with the guard loop encircling the neck of the bottle and the longitudinal arm extending out from said neck, whereby when the stopper is removed, the guard loop with its attached arm serves to hold the end of the stopper out of contact with a supporting 25 surface.

10 In testimony, that I claim the foregoing as my own, I have hereto affixed my signature in the presence of two witnesses.

15 THOMAS ARTHUR JOHNSON.
